UNITED STATES PATENT OFFICE.

WILLIAM A. MCLEAN, OF ROCHESTER, NEW YORK, ASSIGNOR OF ONE-HALF TO BERTRAM S. FENNER, OF ROCHESTER, NEW YORK.

AIR GUN.

Application filed May 5, 1922. Serial No. 558,800.

To all whom it may concern:

Be it known that I, WILLIAM A. MCLEAN, of Rochester, in the county of Monroe and State of New York, have invented certain 5 new and useful Improvements in Air Guns; and I do hereby declare the following to be a full, clear, and exact description of the same, reference being had to the accompanying drawings, forming a part of this specification, and to the reference numerals 10 marked thereon.

My present invention relates to ordnance and, more particularly to air guns, and it has for its object to provide a simple, efficient and durable air rifle suitable for use as a small caliber sporting or target rifle. The improvements are directed to features of construction whereby the gun is made simple to operate and is easily taken apart for 15 cleaning, adjustment and repair. The improvements are further directed toward improving the valves so that they will remain tight and admit of high pressure being developed and this without the corrosive effect 20 usually produced as a result of condensation in connection with compressing the air. To these and other ends the invention consists in certain improvements and combinations of parts, all as will be hereinafter more fully 25 described, the novel features being pointed out in the claims at the end of the specification.

In the drawings:

Figure 1 is a side view of an air rifle constructed in accordance with and illustrating one embodiment of my invention;

Figure 2 is an enlarged view of the same partly broken away and partly in vertical section through the stock;

Figure 3 is a cross section on the line 3—3 of Figure 2;

Figure 4 is an enlarged cross section on the line 4—4 of Figure 1;

Figure 5 is a fragmentary top plan view 45 of the breech in the position of Figure 2;

Figure 6 is an enlarged fragmentary sectional view through the breech;

Figure 7 is a fragmentary longitudinal sectional view through the pump cylinder 50 and piston, and

Figure 8 is a cross section through the breech block taken substantially on the line 8—8 of Figure 6.

Similar reference numerals throughout 55 the several views indicate the same parts.

My improved gun preferably includes a rifled barrel in which a special projectile is used that is impelled by the sudden release into the chamber of compressed air from a high compression chamber in which it is 60 stored after its generation in an adjoining pump chamber. The gun has the usual exterior form including a butt 1, stock 2, trigger 3, trigger guard 4 and barrel 5 beneath which latter and coextensive therewith in the present embodiment is a pump cylinder 6. A cap 7 on a pump rod 8 projects from the front end of the pump cylinder 6 near the muzzle and the gun is charged 65 by one or several strokes of the pump induced by pulling out the rod 8 and then forcibly returning it by placing the butt against the shoulder and resting the button 7 against the ground, a tree or a wall. At the front end the barrel 5 and pump cylinder 6 are held together by a band 9 in which is formed the front sight 10 and to which the pump cylinder is locked by a screw 11 passing therethrough and also securing a bearing collar 12 in a front end of the pump 70 cylinder for the pump rod 8, all as shown in Figure 3. A similar middle band 13 is provided that rests in the stock 2 to which it is held by a screw 14'. 75

The rear end of the barrel and the chamber 80 14 contained therein is held in a solid breech block 15 by a set screw 16 which breech block carries the rear sight 17. The gun operates with a bolt action, the bolt 18 being reciprocable through the use of the 85 usual knob or handle 19 between guiding lugs 20 at the rear and top of the breech block 15. At the front end of the bolt is a non-metallic seat 21 of fiber or similar material that is noncorrosive and is adapted to 90 tightly engage the rear end of the chamber 14 and barrel 5, as shown in Figure 6. It is locked in such air tight engagement by the rotation of the bolt 18 on which is a lug 22 that locks with a cam shoulder 23 at the 95 front of the lug 20 in the ordinary manner, the shoulder 23 being slightly inclined and the lug 20 being provided with a slot 24 at the top to accommodate the lug 22 when the bolt is withdrawn as in Figure 2. In this 100 position the chamber is open and what may be termed by analogy and convenience a firing pin 25 at the front end of the bolt is exposed within the notch or cutaway portion 26 at the center of the breech block 15. 105

to receive the projectile or bullet 27 that is inserted on the pin and carried into the position of Figure 6 in the chamber 14 with the forward motion of the bolt. This bullet is 5 preferably of the double conical form shown in Figure 6 with a conical cavity in its rear end to receive the pin 25 which shape also contributes to the ballistic properties of the bullet in a way that need not be here explained. The pin 25 is preferably screwed into the bolt at 28 and has a shoulder 29 that holds the seat 21 in place in a cavity in the bolt end.

The rear end of the pump cylinder or tube 15 6 is preferably threaded into the breech block 15 at the front end of the latter below the barrel 5, as best shown in Figure 6, and contains a pump chamber 30 in which operates a piston 31 of the usual construction at 20 the rear end of the pump rod 8. Between this piston and a shoulder 32 on the pump rod is a lubricating block 33 formed with an annular groove in which is an absorbent packing 34 that, once soaked with oil, not 25 only lubricates the pump for a long period of use but causes oil in sufficient quantity to be useful to find its way through the air passages and mechanism hereafter described. Fitting within the end of the pump tube 6 30 is a shell 35 having shoulders 36 engaging the end of the tube to define its position, which shell forms the high compression chamber 37. The shell is formed with a port or passage 38 communicating with the pump chamber 30 to receive charges of air therefrom under the control of a check valve 39, and in this way the high compression chamber 37 is charged to the desired degree.

Threaded into the breech block from the 40 rear in alignment with the pump cylinder in chamber 37 is a valve casing 40 having a non-metallic washer 41 at its front end, also preferably of fiber that makes a tight contact with the end of the shell 35 holding it 45 in place in its tube and also constituting the rear wall of the chamber 37. The valve casing is secured in this position by a lock nut 42. The washer 41 has a seat 43 therein for a valve 44 that controls the escape of the compressed air from chamber 37 to a passage 45 in the valve casing 40 through which the valve stem 46 projects. This passage 45 leads to a vertical passage 47 formed in the valve casing 40, the breech block 15 and the barrel 5 to open into the chamber 14, so that 55 when the valve 44 is suddenly released or unseated the highly compressed air from the chamber 37 is admitted to the rifle chamber 14 behind the bullet 27 and in this way the gun is fired. The shape and manner of 60 cooperation of the valve 44 with its non-metallic seat 43 is important in practice and is such that the valve continually grinds its own seat and remains tight. It also does not 65 become foul from corrosion or the effects of

the condensation of moisture that is bound to occur where air is compressed and expanded. A spring 48 interposed between the check valve 39 and the head of the valve 44 presses them in opposite directions toward 70 their respective seats and is more particularly a spring for the check valve 39.

Surrounding the valve stem 46 and the valve casing 40 which are cylindrical and guided upon the latter is a reciprocatory 75 hammer sleeve 49 having a shoulder 50 at the front end thereof between which shoulder and a nut 51 on the rear end of the valve casing is confined a coil spring 52. The rear end of the tube 49 is closed by a cap plug 80 53 threaded therein which cap plug normally engages the rear end of the valve stem 46 as shown in Figure 6 and holds the valve unseated, the spring 52 being superior to the spring 48 which latter may be relatively 85 light.

The gun is cocked by withdrawing the bolt 18 and when rotated by the knob 19 for this purpose to release lug 22 from shoulder 23, a pin 55 on the rear end of the bolt engages the cap 53 as shown in Figure 2 and draws it back together with the hammer sleeve 49 which compresses the firing spring 52. This permits the valve 44 to seat and the gun may be charged with 95 air. The sleeve 49 is held in the cocked position by a detent 56 on a trigger 3, pivoted at 57 in a slot 58 in the under side of the breech block 15. In so doing the detent 56 engages the front end of the sleeve 49 in 100 the region of the shoulder 50 which is cut back for the purpose as shown to insure an effective engagement. Upon pulling the trigger the sleeve 49 is released and the cap 53 forcibly strikes the end of the valve stem 105 46 unseating the valve 44 and discharging the bullet as heretofore described.

The trigger spring 59 is a flat breech spring lying on the under side of the breech block to hold the detent portion 56 in position to engage, and I prefer to secure the spring by confining it under a shoulder 60 on a bolt 61 threaded into the breech block and which fastens the latter to the stock 2 110 by means of a nut 62.

It will be observed that all of the breech mechanism can easily be taken down or removed for cleaning, oiling or repair. By removing the cap plug 53 and nut 51 the firing spring 52 may be removed and also 115 the sleeve 49. By then removing the lock nut 42 the whole valve casing 40 and valve 44 may be removed to the rear end of the breech block. This may be followed by the removal of spring 48 and check valve 39 120 with or without the shell 35 of the compression chamber. The pump tube 6 may be removed in a forward direction from the front end of the breech block and the shell 35 and contents with it if desired unless 125 130

these parts have been removed as previously described. The bolt 18 may now also be withdrawn in a rearward direction and this gives access to the barrel from either end 5 in the manner of an ordinary bolt action rifle.

I claim as my invention:

1. In an air gun, the combination with 10 a breech-block, of a pump tube extending into the same from the front end thereof, and containing a pressure chamber and a pump chamber and a valve casing extending into the breech-block from the rear end and meeting the pump tube to constitute one 15 end wall of the pressure chamber.

2. In an air gun, the combination with 20 a breech-block, of a pump tube secured therein, a removable shell contained in the secured end of the pump tube and constituting a pressure chamber having an intake port communicating with the pump tube, and a valve casing removably secured in the breech block and cooperating with the shell to constitute one end wall of the 25 pressure chamber, the removal of the valve casing permitting the removal of the shell through the breech-block.

3. In an air gun, the combination with 30 a breech-block, of a pump tube secured in the front end thereof, a removable shell contained in the secured end of the pump tube and constituting a pressure chamber having an intake port communicating with the pump tube, said shell being provided with 35 a shoulder abutting the end of the pump tube, and a valve casing removably secured in the breech block and cooperating with the shell to clamp the shoulder thereon in place and constitute one end wall of the pressure 40 chamber, the removal of the valve casing

permitting the removal of the shell through the breech-block.

4. In an air gun, the combination with a 45 breech-block, of a pump tube secured in the front end thereof, a removable shell contained in the secured end of the pump tube and constituting a pressure chamber having an intake port communicating with the pump tube, a check valve and spring in the shell controlling said port and removable 50 through the end of the shell, and a valve casing removably secured in the breech-block and cooperating with the shell to constitute one end wall of the pressure chamber, the removal of the valve casing permitting 55 the removal of the shell through the breech-block or the spring and chuck valve from the shell.

5. In an air gun, the combination with 60 a breech-block having a pump tube secured therein, of a detachable release valve casing secured in the breech block and a removable pressure chamber shell carried in the secured end of the pump tube, said parts being aligned and removable in the order named 65 through the rear end of the breech block.

6. In an air gun, the combination with a 70 breech block having a pump tube secured therein, of a detachable release valve casing secured in the breech block and a removable pressure chamber shell carried in the secured end of the pump tube, said parts being aligned and removable in the order named 75 through the rear end of the breech block, the pressure chamber shell having an intake port and containing a check valve and spring controlling the same and removable through the rear end of the shell.

WILLIAM A. McLEAN.
